UNITED STATES PATENT OFFICE

CLAUDE V. MARTIN, OF NORWALK, OHIO, ASSIGNOR TO MAPLE CITY RUBBER COMPANY, OF NORWALK, OHIO, A CORPORATION

BALLOON PROCESS AND ARTICLE OF MANUFACTURE

Application filed February 1, 1933. Serial No. 654,756.

This invention provides a novel process of mounting rubber articles, such as toy balloons, upon a base in such a manner that a firm adherence between the balloon and base 5 will be obtained.

Heretofore difficulty has been experienced in securing such articles to a suitable base without likelihood of the base separating from the article; and where, as is usually the 10 case, the balloon is formed into a novelty shape so that, when inflated, it will represent a form such as an animal, bird, or the like. It is obvious that the effective appearance of the balloon is greatly enhanced by the provision of a suitable base or supporting member which should be permanently fastened to the balloon so as not to become detached therefrom during the life of the balloon.

The present invention is designed to over- 20 come the objections of separation between the base or support and the balloon at any time, assuring a permanent union therebetween.

In accordance with the present invention, there is provided a suitable base or support- 25 ing member for attachment to the balloon, which base is provided with an opening over which on the underside of the base, there is placed a securing member comprising a thin sheet or disc of elastic material, such as rubber, which is adapted to be secured to the bal- 30 loon by a suitable cementing material.

Since the difficulties experienced in connection with articles of this character as produced prior to this invention have resulted 35 from a difficulty in obtaining a close or intimate contact between the contacting surfaces, a further object of the present invention is to provide a novel process for securing the base to the balloon.

40 For the accomplishment of this object it is proposed to force the cement covered attaching member through the opening in the base by utilizing the pressure of inflation of the balloon, which pressure of inflation is caused 45 to press the balloon against the base after completion of all mechanical and manual operations.

Specifically, the attaching of the base to the 50 balloon is carried out by utilizing holding instrumentalities for the inflated balloon, which

holding instrumentalities frictionally restrain the inflated balloon against movement, and cause the balloon to press against the base until the adhesion between the base and the balloon has become permanent. For fa- 55 cilitating the necessary intimate contact be- between the securing member and balloon, the bottom of the holder is provided with an up- standing lug adapted to register with the hole in the aforesaid base, the pressure of the sides 60 of the holder against the inflated balloon causing the latter to press upon the base to force the said base against the bottom of the holder which causes the attaching member to be pressed through the opening and against 65 the envelope of the balloon, thereby maintain- ing a positive pressure between the balloon and attaching member during the setting of the cement.

The invention will be more clearly under- 70 stood by reference to the accompanying draw- ing, in which—

Figure 1 is a view illustrating a novelty balloon secured to a base, or supporting mem- 75 ber.

Figure 2 is a view of the bottom of the base or supporting member illustrating the at- 80 taching member applied thereto.

Figure 3 is a fragmentary view in section, showing the balloon adhered to the said at- 85 taching member.

Figure 4 is a top view of a holder in which the balloon is adapted to be secured or held during the cementing operation, the outline of the balloon envelope being shown in dotted 85 lines.

Figure 5 is a partial sectional view through the holder showing the means of forcing the attaching member against the envelope in intimate contact therewith so as to produce 90 the required close union between the patch and balloon.

Figure 6 is a sectional view taken on the line 6—6 of Figure 5, looking in the direc- 95 tion of the arrows.

Figure 7 is an enlarged fragmentary sec- 100 tional view showing the details of the position of the respective parts during the cementing operation.

Referring more particularly to the draw-

ing, it will be seen that the envelope A of the balloon, being shown for purposes of illustration as simulating a duck, is secured to a suitable base, or supporting member, B, 5 and has a usual valve C by which the balloon may be inflated.

The base B is formed with a hole 1 therein over which hole and on the underside of the base B, there is cemented an attaching member, which is desirably of thin, flexible rubber. This member has applied to the surface thereof which engages with the balloon A, a layer of suitable adhesive material, such as rubber cement, by means of which the member 2 may be firmly adhered to the balloon A.

In order to bring about this adhesion, the permanent character of which is dependent upon the intimacy of contact between the cemented surface of the securing member 2 20 and the balloon A, there is provided a holder which is adapted to hold and restrain the balloon against movement, when the balloon is in inflated condition.

This holder may be of varying detail, but 25 is illustrated as comprising a bottom 3, to which is suitably secured the holding member which is, conveniently, of generally U-shaped cross section and comprises the up-standing walls 4 and the bottom 5. This 30 bottom has an opening cut through for the reception of an upwardly projecting lug 6, suitably secured in the base 3 of the holder, which lug is adapted to act upon the attaching member 2 to force the said attaching member upwardly through the opening 1 in the base under the pressure of inflation of the balloon, so as to intimately engage the attaching member with the balloon A. It will be seen that the balloon is inflated sufficiently to be restrained against displacement when inserted between the sides 4 of the holder, under which conditions the balloon envelope is forced inwardly by pressure against the lug 6, as will be seen at 7; and 40 the attaching member 2 is similarly projected through the opening 1, by the downward pressure of the inflated balloon, as is indicated at 8, so that the balloon and attaching member are pressed together in intimate 45 contact until the preliminary adhesion there-between becomes permanent.

When the base B has been secured to the balloon A, and the cement has thoroughly set, the balloon, with its attached base, is deflated and removed from the holder when the adhering surfaces take the position shown in Figure 3.

It will be understood that the balloon is inflated sufficiently so that it will be frictionally held between the sides 4 of the holder and distorted sufficiently to press upon the base B with sufficient force to cause the lug 6 to press the attaching member, which is intermediate the lug and the balloon, against 65 the balloon by reason of the pressure of in-

flation, thus giving a close engagement between the surfaces of the securing member and balloon, thereby greatly enhancing the adhesive force of the cement on the contacting surfaces. As soon as the cement has become 70 stuck, the balloon and base are removed by hand from the holder, initial temporary adhesion between the balloon and base having become permanent in nature during the time the balloon is restrained in the holder. The 75 balloon is then deflated, and the article is removed from the holder and ready to be packed for shipment, or sold, as the case may be.

Having thus described my invention, 80 what I claim as new and desire to secure by Letters Patent of the United States, is—

1. The method of applying a base to a rubber balloon or the like, which comprises securing to the base an attaching member for 85 joining the base and balloon, causing preliminary adhesion between the attaching member and balloon, and inflating the balloon so that its pressure of inflation causes it to bear and remain firmly against the said 90 adhesion point of preliminary adhesion aforesaid, whereby to cause the adhesion to become permanent.

2. The method of applying a base to a rubber balloon or the like, which comprises these 95 steps, applying a balloon to a base with a point of temporary adhesion, inflating the balloon, and utilizing the pressure of inflation to press the balloon firmly against the said adhesion point until the adhesion connection becomes permanent.

3. The method of applying a base to a rubber balloon or the like, which comprises securing to the under side of a base and below an opening therein, an attaching member of an elastic nature, disposing a balloon above the base at the opening, causing preliminary adhesion between the balloon body at a point above the opening and the portion of the attaching member at said opening, and inflating the balloon to press on the base in such a way as to force the portion of the attaching patch at the opening, through the opening, and also by the pressure of inflation to hold the balloon in intimate contact with the attaching member at the point of preliminary adhesion, until the adhesion becomes permanent.

4. As a new article of manufacture, in combination, a balloon, a base therefor having an opening therein and adapted to support the balloon when inflated, said base having an attaching member of rubber applied to its under side below the opening, the portion of the rubber attaching member at the opening being pushed through the opening and permanently adhered to the balloon body.

In testimony whereof I affix my signature.
CLAUDE V. MARTIN.
